(57) **CLAIM**

The ornamental design for a display screen with graphical user interface, as shown and described.

DESCRIPTION

The FIGURE is a front view of a display screen with graphical user interface showing my new design.

The outermost broken line is a showing of the display screen and forms no part of the claimed design. The features shown in broken lines in the drawings depict environmental subject matter only and form no part of the claimed design.

1 Claim, 1 Drawing Sheet
